[57] CLAIM

The ornamental design for a wall mounted plastic bag dispenser, as shown and described.

DESCRIPTION

FIG. 1 is a perspective view of a wall mounted plastic bag dispenser embodying our new design, the broken line showing of the wall being for illustrative purposes only.

FIG. 2 is a bottom plan view thereof.

FIG. 3 is a side elevational view taken from the right of FIG. 1, the side opposite being a mirror image thereof. The rear of the dispenser is flat and unornamented.
